UNITED STATES PATENT OFFICE.

SAMUEL J. MATHEWS, OF SAPULPA, OKLAHOMA, ASSIGNOR TO B.-B. MANUFACTURING AND DRILLING COMPANY, A CORPORATION OF DELAWARE.

WELL-DRILLING APPARATUS.

Application filed July 19, 1920. Serial No. 397,217.

To all whom it may concern:

Be it known that I, SAMUEL J. MATHEWS, a citizen of the United States of America, residing at the city of Sapulpa, State of Oklahoma, United States of America, have invented a certain new and useful Well-Drilling Apparatus, of which the following is such a full, clear and exact description as will enable anyone skilled in the art to 10 which it appertains to make and use the same, reference being had to the accompanying drawings, forming part of this specification.

My invention relates to well drilling apparatus, particularly of the class shown and described in Patent No. 1,077,620 granted to me November 4, 1913, and its principal object is to provide an improved drill bit capable of operating efficiently under direct 20 drive by a high speed motor. Other objects and advantages of my invention will appear from the following more detailed description.

In the accompanying drawing which illustrates one form of device in accordance with my invention, Fig. 1 is a view showing the device in position in a well. Fig. 2 is an enlarged side view of the bit. Fig. 3 is a view of the bit taken at right angles to Fig. 30 2, and Fig. 4 is a bottom plan view of the bit.

5 indicates a well casing in which the motor casing 6 is suspended by means of a rope or cable 7. The motor casing 6 contains any suitable form of high speed motor, such for instance, as shown in my prior patent above referred to. The motor in the casing 6 drives a tool shaft 8, the lower end of which is secured to a 40 boring head 9. The boring head 9 is provided with two pairs of abrasive bits 10 and 11 respectively. These bits are formed of suitable abrasive material, preferably carborundum. The bits 10 are of such diameter as to pass down through the well casing 5 and are rigidly carried by the boring head 9. The bits 11 are adapted to project beyond the well casing 5 so as to produce an enlarged passage through which 45 the casing can be lowered as shown in Fig. 1. These bits 11 are pivoted to the boring head 9 at 12 so that they will assume a vertical position to permit the boring head to pass through the well casing when not 50 rotating, and are brought to their horizon-

tal operating position by the centrifugal force developed by the high speed of rotation of the tool. 13 is a stem projecting downwardly from the boring head 9 and carrying a pilot bit 14 which is also formed 60 of carborundum or other similar material. The pilot bit 14 is made substantially semi-circular in cross section and it is provided at its central point with a recess 15 adapted to form a slender centering cone 65 which may be broken or crushed by the weight of the descending tool.

As the pilot bit is positioned a substantial distance below the main bit a water reservoir is formed at the bottom of the well 70 which will contain sufficient water to lubricate both the pilot and main bit. The high speed of the bit, which may be from 1000 to 2000 revolutions per minute, permits the extension members of the bit to be 75 thrown into their working position by centrifugal force alone. This enables me to produce an expansion bit without the use of springs and one which consequently may be 80 passed through the well casing without any 85 liability of becoming caught therein.

I claim:

1. In a device of the class described, the combination with driving means, of an abrasive bit driven at relatively high speed thereby, said bit being provided with a recess at its neutral point for forming a frangible centering cone.

2. In a device of the class described, the combination with driving means, of a main 90 bit of abrasive material, and a pilot bit also of abrasive material, said pilot bit being of less diameter than said main bit and positioned a substantial distance below the same.

3. In a device of the class described, the combination with driving means, of a plurality of abrasive bits positioned at different levels, one of said bits being provided with a recess at its neutral point for forming a 100 frangible centering cone.

4. In a device of the class described, the combination with driving means, of a bit of abrasive material, said bit being substantially semicircular cross section and provided 105 at its neutral point with a recess for forming a frangible centering cone.

5. In a device of the class described, the combination with a main abrasive bit having a flat underface, of a pilot bit also of abra- 110

sive material positioned a substantial distance below said main bit.

6. In a device of the class described, the combination with a main bit of abrasive material provided with a flat underface, of a pilot bit also of abrasive material and positioned a substantial distance below said

main bit, said pilot bit being provided at its neutral point with a recess for forming a frangible centering cone.

In testimony whereof, I have hereunto set my hand and affixed my seal.

SAMUEL J. MATHEWS.
